SHOE

Herman B. Delman, New York, N. Y.

Application September 17, 1949, Serial No. 5,046

Term of patent 3½ years

(Cl. D7—7)

To all whom it may concern:

Be it known that I, Herman B. Delman, a citizen of the United States of America, residing in New York, county of New York, and State of New York, have invented a new, original, and ornamental Design for a Shoe, of which the following is a specification, reference being had to the accompanying drawing, forming part thereof.

Fig. 1 is a front perspective view of a shoe, showing my new design.

Fig. 2 is the opposite side as shown in Fig. 1.

I claim:

The ornamental design for a shoe, substantially as shown.

HERMAN B. DELMAN.
